UNITED STATES PATENT OFFICE.

ARTHUR WADSWORTH, OF NEW YORK, N. Y.

METHOD OF OPERATING THE SECONDS-HAND IN STOP-WATCHES.

Specification of Letters Patent No. 31,840, dated March 26, 1861.

To all whom it may concern:

Be it known that I, ARTHUR WADSWORTH, of New York, in the county and State of New York, have invented a new and Improved Method of Operating and Arranging Independent Seconds-Hands; and I do hereby declare that the following is a full and exact description of the same, reference being had to the accompanying drawings and to the letters of reference marked thereon.

On the spindle A of the common seconds hand, a wheel B is placed, so as to turn with said spindle. On the spindle, D, of the hour or main hands, a similar wheel, C, is placed turning loosely on the same, and having the independent hand E attached. The wheels, B, and, C, must have both the same number of teeth either sixty 10 or one hundred and twenty.

An intermediate wheel F arranged to gear into both wheels, B, and, C, so as to communicate the power from the wheel, B, to the wheel, C, is arranged on an arbor fast 15 to a slide, G, capable of turning loosely on said arbor. This slide, G, is operated by a lever, I, one end of which projects through the rim, H, of the watch casing. By means of this lever I the slide G is moved in such a 20 manner as to bring the wheel, F, either in gearing with both the wheels, B, and, C, or to bring said wheel F out of gear, from the wheel, C, and only in connection with

the wheel, B, in which latter position the movement of the independent hand E, will 35 be stopped.

A pointed projection, O, of the lever, I, works into notches in the spring catch, J, by which the motion of said lever, I, is determined. Against the teeth of the wheel, C, 40 a small spring, S, is made to operate, so as to produce a slight stoppage to said wheel after the passage of each tooth, which, although very small, so as not to interrupt the regular motion of this wheel, will be, 45 at the extreme point of the independent hand E, sufficiently marked to indicate the seconds or half seconds.

I do not claim working the independent seconds hand from a wheel placed on the 50 spindle of the usual seconds hand, and connected together by means of an intermediate wheel, nor do I claim placing a stop spring against the wheel of the independent seconds hand spindle; but,

What I claim as my invention and desire to secure by Letters Patent is—

The manner of operating the intermediate wheel F by means of a lever I in combination with a spring J, when arranged for 55 the purpose substantially as specified:

ARTHUR WADSWORTH.
